 tion of Illinois

Filed July 2, 1962, Ser. No. 286,898
 3 Claims. (Cl. 83—163)

This invention relates to devices for controlling and guiding continuous form stationery through business machines.

The common method of driving continuous form stationery through a business machine is by engagement of the control punched holes in the side margins of the stationery with pins extending radially outwardly from a driven wheel. The side margins of the stationery may be cut therefrom by a pair of vertically spaced cutting wheels, one of which is coaxially mounted with the driven wheel, or the pinwheel may be used as a feeding device for the stationery without trimming. The stationery generally departs from the pin wheel in a linear horizontal path, parallel to the top of the pinwheel. At the point where the pins on the pinwheel are supposed to become disengaged with the feed holes of the margin of the stationery and begin to "disappear" below the plane of the stationery, the pins do not impart a true involute motion to the driven stationery. There is a tendency for the pins (being disposed in an increasingly more acute angle in relation to the stationery) to push the marginal material down from the normal plane of travel. This tendency of the pins to "catch" on retraction from the feed holes, frequently causes jamming of the machine due to the fact that the driving means is disposed in a relatively confined space and the stationery travels at rather high speeds through the machine. Such jams require a significant amount of time and effort to dislodge the paper and place the machine again in operation.

Another problem present in current trimming devices is a tendency for the stationery to "buckle" or rise off the drive wheels. This is believed to be caused by the relatively flexible nature of the paper and also is due to folds at the transverse lines of weakening which are formed in the continuous form stationery. Efforts to restrain this relatively vertical movement have resulted in substantially retarding the generally horizontal path of travel of the trimmed marginal portion of the stationery. This further contributes to the tendency of the trimmer to jam, or at least, limit the speed of the trimmer.

It is therefore an object of this invention to provide a new and improved paper control for pin-fed stationery devices.

It is another object of this invention to provide a new and improved paper control having means for maintaining the stationery in a linear path of travel past the drive wheel.

It is still another object of this invention to provide a new and improved paper control having means tending to lift the material of the stationery off the drive wheel at the proper point of disengagement with the drive wheel pins.

It is yet another object of this invention to provide a new and improved paper control having means giving the marginal material of the stationery a moving support from the point of its tangential contact with the periphery of the drive wheel to a point past the disengagement of the drive pins with the stationery.

It is a further object of this invention to provide a new and improved paper control having means for limiting the vertical movement of the stationery, said means urging the stationery itself to assume a generally linear path of travel.

Other objects, features and advantages of the present invention will be apparent from the following description of the preferred embodiment illustrated in the accompanying drawings, in which:

- 5 FIGURE 1 is a fragmentary side elevational view in partial phantom outline showing a general embodiment of this invention in a trimmer mechanism;
- 10 FIGURE 2 is a fragmentary front elevational view taken along the line 2—2 of FIGURE 1;
- 15 FIGURE 3 is an enlarged fragmentary view of a portion of the device shown in FIGURE 2;
- 20 FIGURE 4 is a section view taken along the line 4—4 of FIGURE 3;
- 25 FIGURE 5 is a section view taken along the line 5—5 of FIGURE 4;
- 30 FIGURE 6 is a section view taken along the line 6—6 of FIGURE 5; and
- 35 FIGURE 7 is a section view taken along the line 7—7 of FIGURE 5.
- 40 The device of this invention chosen for illustration is embodied in a trimmer mechanism 10 which is designed to receive stationery 11 at the front 12 thereof for driving the stationery through the trimmer and removing marginal material therefrom. Since each trim unit can also act as
- 45 a "pinwheel feed unit" without trimming, the use of the present invention in this apparatus will be quite apparent. A mounting bar 13 extends across the width of the front of the trimmer on which is mounted a pair of trim units 14 and 14a which drive the stationery through the trimmer 10 and may also remove the marginal material from the stationery. The trim units 14 and 14a are intersected by a pair of spaced driven shafts 15 and 15a of substantially hexagonal peripheral configuration which are generally parallel to each other and to the mounting bar
- 50 13. The driven shafts 15 and 15a transmit rotational force to the trim units from a pulley wheel 16 which is operatively connected to a power source (not shown) by means of a belt 17. A measuring means or scaled bar 18 extends generally parallel to the mounting bar and
- 55 driven shafts and cooperates with the indicator 19 on each trim unit to determine the distance between the units. The indicator 19 may be mounted to the trim unit by means of a slideable post and slot arrangement (not shown) to permit limited vertical movement of the indicator
- 60 when the trim unit is in the "no trim" position as will be described later. The stationery 11 has a margin 24 at each side thereof, sometimes defined by an inner line of weakening 24a and the outer edge of the stationery. Formed in the margins are control punch holes 23.
- 65 The stationery is driven through each trim unit by means of a pinwheel 21 which has a plurality of radially extending upstanding pins 22 sequentially engaging the control punch holes 23 in the margin 24 of the stationery to advance the stationery in a generally linear path. The
- 70 marginal material of the stationery is removed therefrom by the cooperation of a pair of vertically spaced cutting discs 25 and 25a which are mounted on shafts 15 and 15a, respectively, and are adjusted, by means explained later, to cut close beside the line of weakening 24a. The combination of the diameter of the discs 25 and 25a and the distance between the shafts 15 and 15a upon which they are mounted is such that portions of their cutting edges 26 and 26a, respectively, overlap in an area adjacent the pinwheel 21. It is this slight overlapping which maintains the discs in operable relation when the discs are rotated by appropriate connecting means from the driven shafts 15 and 15a for cutting stationery driven through the unit by the pinwheel 21.
- 75 Impaled on the upstanding pins 22 of the pinwheel 21 and driven thereby is a moving element 27 which has a number of openings in excess of the number of pins 22. In the illustrated embodiment of this invention the moving

ing element 27 includes an elongate tape or belt 28 of resilient material, such as Mylar or the like, which has a plurality of motion receiving means or holes 29 therein adapted to be impaled by the pins 22 of the pinwheel. Also included in element 27 is an idler wheel 30 around which belt 28 passes. The idler wheel 30 is journaled for free rotation at 30a and is positioned from the pinwheel 21 so that a portion of the belt 28 travels in general parallelism with the line of paper separation from the pinwheel 21. The idler wheel 30 is spaced from the pinwheel 21 a sufficient distance to maintain the belt 28 in tension. Since the belt is driven by the same element as the paper it travels at essentially paper speed.

When stationery reaches a point on the pinwheel generally on a line with the pin designated 31 in FIGURE 4, it has its marginal portion cut by the cooperative action of the discs 25 and 25a. That marginal portion 24 then travels a horizontal path out of the trim unit where it is deflected into an appropriate waste receptacle (not shown) by the deflector 19b which intersects the path of travel of the marginal portion 24. As the marginal portion 24 assumes this horizontal path the pins are pulled downwardly out of the holes 23 of the margin. That is, the pins continue their rotational movement on a path divergent from that of the marginal material 24. In so doing the pins 22 being assuming an angular relation with respect to the holes 23, as illustrated by the pin designated 31a in FIGURE 4, rather than a perpendicular relation. In such an angular relation portions of the extremities of the pins 22 will be further along the path of travel of the marginal material 24 than will be the furthest portion of the edge of the respective holes 23. As the pin 22 continues its travel around the periphery of the pin wheel 21 such a relationship will create a tendency for the pin to pull the marginal material 24 along with it on its peripheral line of travel as the pin recedes from the hole 23, rather than permitting the marginal material 24 to travel a true horizontal path. This is indicated by the dotted line 38 in FIGURE 4. Since trimmer mechanisms are driven at extremely high speeds such a deflection of the path of travel of the marginal material 24 can cause a serious jam of paper within a trim unit in an extremely short time. However, with a moving element, such as the Mylar belt 28, positioned on the pinwheel underneath the marginal material 24 this deflection is prevented. The belt is in tension and therefore more taut than the paper margin, travels at the same speed and generally parallel with the margin 24 and thus tends to "lift" the margin from the pins of the pinwheel. Therefore the paper assumes a generally linear or true tangential linear path of travel from the pinwheel at the point designated by the pin 31 (FIGURE 4) and no jam can result.

As the marginal material 24 is advanced from the pinwheel 21 it may also have a tendency to rise or "buckle" vertically, possibly due to transverse lines of weakening which may be present in the stationery 11 being driven through the trim unit 14. This can cause the margin 24 to become disengaged from the pinwheel 21 and interrupt the operative advancing relation therebetween. To prevent this, there is mounted above the path of travel of the marginal material 24 and generally parallel thereto a means for maintaining stationery in driving engagement with the pin wheel and limiting the vertical movement thereof, comprising a vertical paper deflecting means or yieldable spaced guide means 32. This guide 32 is a generally flat, thin, elongate strip of resilient material such as a flat steel spring 33 positioned above the path of travel of the stationery in the area of the pinwheel and having a longitudinal slot 34 extending in the direction of paper travel for permitting the passage of the radially extending pins 22. The spring 33 is yieldable in a vertical direction and is mounted to the trim unit behind the point of paper separation from the pinwheel at one end 35 by appropriate means such as screw 35a so that

it will dampen vertical movement of the marginal material 24 without limiting the horizontal movement thereof. The paper deflecting means 32 combines with the moving element 27 to form a channel through which the marginal paper material 24 must pass, at least one side of which is a movable member. It is possible that a second moving element 27, allochirally related to the moving element 27 in the illustrated embodiment, could be used in place of the paper deflecting means 32.

Positioned on the front of the trim unit and in the path of paper flow is a paper hold-down or register means 36 for registering the holes of the paper on the pins of the pinwheel and initiating the flow of stationery into the trim unit. The hold-down means 36 includes a roller 37 having portions of different diameters on a common center. The roller 37 is rotatably mounted on an arm 38 pivotally mounted to the unit at 38a and spring loaded by a helical spring 38b for urging the roller toward the pinwheel 21. In its portion of greater diameter, 37a, the wheel 37 rests against the periphery of the pinwheel adjacent that portion on which the belt and the marginal material are impaled and driven thereby. In its portion of least diameter, 37b, the wheel 37 is recessed a sufficient distance to permit the free rotation of the pinwheel 21 so that the pins 22 will not strike the wheel. Portions 37c and 37c' of the wheel 37 are of the same diameter which is less than portion 37a but greater than 37b. The diameter of portions 37c and 37c' is such that the wheel, in those portions, does not contact the periphery of the pinwheel but rather is a sufficient distance away so that there will be space for a set of stationery between portions 37c and 37c' and the surface of the pinwheel 21. However, the wheel 37 is sufficiently close to the pinwheel 21 in the areas 37c and 37c' that, in combination with its rotational movement imparted by the pin wheel 21 in the area 27a, the wheel urges the holes of the stationery in registry with the upstanding pins of the pin wheel and also tends to smooth out any transversely extending creases which may be transformed into upstanding buckles in the stationery 11.

For adjusting the trim units to cut stationery of different marginal widths, the cutting discs 25 and 25a are secured to the driven shafts by interconnecting means 60 and 60a. Interconnecting means 60 and 60a include disc holders 40 and 40a, respectively, which are appropriately interconnected with collars 41 and 41a, respectively, on the driven shafts 15 and 15a by suitable means, such as a slot 42 in the holder and a key 43 on the collar. This interconnection transmits rotational force from the driven shafts to the discs but permits the discs and holders to be moved laterally relative to the shafts and to the pinwheel which is an integral part of the collar 41a. Disc 25a is resiliently urged against disc 25 by means of a plurality of coil springs 44 which reside in the disc holder 40a and extend laterally in abutting relation to the side of the pinwheel 21 so that lateral movement of the collar 41 will correspondingly cause lateral movement of the collar 41a. For adjusting the position of the discs there is a manually operable traversing unit 45 consisting of a screw member 46 extending generally parallel to the shaft 15 and a threaded member or carrier 47 mounted thereon. Carrier 47 extends substantially normal to the longitudinal axis of both the shaft 15 and screw 46. At its lower end carrier 47 mounts a bearing 48 which extends into the circumferential groove 49 of the collar 40 for transmitting lateral movement to the disc 25 (therefore the disc 25a) by rotation of the screw 46. A suitable indication means may be formed on the unit for determining the relative position of the cutting discs 25 and 25a. Disc holder 40a is of greater lateral width than the disc holder 40. The lateral movement of the disc holder 40a will be limited by the snap ring 66, and it can be seen that, due to the greater cross-sectional lateral width of the disc holder 40a, this holder and its associated disc 25a is not capable of as great a lateral movement away from the pinwheel 21 as is

the disc holder 40 and its associated disc 25. Thus when the disc holder 40 has been moved laterally along the collar 41 to a point where the disc holder 40a has moved laterally along the collar 41a until it rests against the snap ring 66, the disc holder 40 is still capable of further lateral movement in the same direction. Such further lateral movement of the disc holder 40 will bring the discs 25 and 25a out of facial engagement, and therefore out of operable association, and they will not cut stationery that is passed between them. When the holders 40 and 40a have both reached their respective limit of lateral movement the blades 25 and 25a will be separated from the disc equal to the distance in lateral cross-section dimension of the two holders. When the blades are so separated they are in what is known as a "no trim" position. When the discs are in the aforementioned "no trim" position the pinwheel still is in operable association with the perforate margin of the stationery for advancing the stationery through the trim unit. When the discs are in the "no trim" position the function of the moving element is of increased importance. When the trim unit is removing marginal material from the stationery, the possible jamming of the marginal material will have substantially little or no effect on the remainder of the stationery being driven through the trim unit, and possibly through an imprinter, because the marginal material is no longer physically associated with the stationery. However, when the margin is not being trimmed the pinwheels are engaging marginal portions of the stationery which remain attached thereto and any deflection or downward pull of that marginal portion can affect the flow of the stationery. Thus jamming of the marginal material of the stationery when the trim unit is in a "no trim" position could cause creasing or tearing of the stationery being fed into the trimmer mechanism and, as the stationery is also being fed through an associated imprinter, could cause nonregistered printing to be transferred thereto. Therefore it is apparent that the moving element is an aid to high speed paper travel in many situations where the paper may be advanced by means of the engagement of a pinwheel with holes in the stationery or in a manner similar thereto.

The trim units are secured to the mounting bar 13 by means of a ring 52 which is press fitted in the base of the trim unit and surrounds the mounting shaft 13. A clamp screw 53 with a manually engageable knob 54 extends radially outwardly of the bottom of the ring 52 for locking and unlocking the unit to the mounting bar. The collars 41 and 41a have an interior configuration for mating with the hexagonal shaped drive shafts. This interior configuration fixes the collars on the shafts for receiving rotational motion from the shafts but permits lateral movement of the collars and their associated elements relative to the drive shafts. Thus the entire trim unit may be laterally moved along the length of the mounting shaft and the driven shafts by loosening the clamp screw 53 and sliding the unit in the desired direction and thereby adjust the units to trim stationery of different widths.

Each trim unit has a cover 54 of clear plastic material which includes a downwardly extending shield 56 for preventing the trimmer operator from coming into contact with the cutting discs and also helps guide stationery into the trimmer. Located below the guide 56 and generally coextensive therewith is a base guide 58 which combines with the guide 56 to form a paper infeed channel into the trimmer. An indicator means may be formed on the top of the cover 54 for indicating the position of the cutting discs.

A trim rewind reel 62 is located at the front of the trimmer below the trim units for receiving the severed margins from the stationery in order to compact the same for disposal. Additional paper guides 20 and 20a are mounted at the front of the trim on the mounting bar 13 to support the center portions of the stationery

being fed into the trimmer. After the stationery passes the trimmer mechanism it is supported on a paper outfeed platform 65 shown in phantom outline in FIGURE 1 and drops from there at the rear of the trimmer 10 to an outfeed shelf (not shown).

Machines for processing continuous form stationery must be able to operate at high speeds without breakdown or unnecessary stoppage of the machine. The device of this invention promotes high speed operation by limiting "buckling" of the stationery by means of the paper deflecting spring and therefore preventing any slippage that might occur in driving the paper. However this elimination of paper buckling and slippage is done without significantly retarding the forward motion of the paper and the trimmer portion thereof. This invention also eliminates a major cause of machine stoppage or breakdown due to paper jamming. A continuous surface which runs over the drive wheel and under the stationery gives the trimmed margin a moving support. This surface tends to "lift" the margin of the stationery off the pinwheel at the point of the disengagement of the driving pins with the paper and therefore prevent the pin from pulling the paper down with it. The device of this invention promotes more rapid and reliable trimmer units in that it provides positive control and guiding of paper being trimmed thereby.

The foregoing detailed description has been given for the clearness of understanding only and no unnecessary limitations should be understood therefrom for some modifications will be obvious to those skilled in the art.

We claim:

1. In a business machine adapted to accept marginally perforated control punched stationery therein, means for controlling and guiding stationery therethrough, comprising: a driven pinwheel mounted on a driven shaft, said pinwheel having generally radially extending pins adapted to engage perforations in said stationery and advance the same through said unit; and means for maintaining said stationery in a generally linear path of travel along a line tangential to a point of separation from said pinwheel and in linear alignment with the pins thereof, including a moving element positioned between said stationery and said pinwheel impaled on and driven by the pins of pinwheel and having a number of openings in excess of the pins on said pinwheel, said moving element having a portion traveling in general parallelism with the line of paper separation from the pinwheel.

2. In a business machine adapted to accept marginally perforated control punched stationery therein, means for controlling and guiding stationery therethrough, comprising: a driven pinwheel mounted on a first driven shaft, said pinwheel having generally radially extending pins adapted to engage perforations in said stationery and advance the same through said unit; and a moving support means for the cut material of the stationery for maintaining said cut material in a generally linear path of travel from the point of its separation from the pinwheel, said means including a movable member comprising a belt impaled on and driven by said pins of said pinwheel and having a number of openings in excess of that of the number of pinwheels, said belt having a portion traveling in general parallelism with a line tangent to the point of paper separation from said pinwheel at substantially paper speed, whereby said cut material portions is prevented from diverging along the periphery of the pinwheel.

3. In a trim unit for trimming perforated marginal material from stationery, means for controlling and guiding stationery therethrough comprising: a driven pinwheel mounted on a first driven shaft, said pinwheel having generally radially extending pins adapted to engage perforations in said stationery and advance the same through said unit; means for cutting said marginal material from said stationery advanced by said pinwheel; moving support means for the cut marginal material of the stationery for maintaining said material in a generally linear path

of travel from the point of its separation from the pinwheel, said means including a movable member comprising a belt impaled and driven by said pins of said pinwheel and having a number of openings in excess of that of the number of pinwheels, said belt having a portion traveling in general parallelism with a line tangent to the point of paper separation from said pinwheel and in linear alignment with the pins thereof at substantially paper speed, whereby said cut material is prevented from following along the periphery of the pinwheel; and means for limiting vertical movement of said cut material through the trim unit including an elongate resilient member closely spaced above the path of travel of the cut material in the area of the pinwheel and being fixedly secured at one end for yielding in a vertical direction to

8
dampen vertical movement of the cut marginal material stationary without limiting horizontal movement thereof.
